UNITED STATES PATENT OFFICE.

ALEXANDER J. BEISTEL, OF MONESSEN, PENNSYLVANIA.

DESIGN FOR A GAME-BOARD.

SPECIFICATION forming part of Letters Patent No. 34,329, dated April 2, 1901.

Application filed March 11, 1901. Serial No. 50,764. Term of patent 14 years.

To all whom it may concern:

Be it known that I, ALEXANDER J. BEISTEL, a citizen of the United States of America, residing at Monessen, in the county of Westmoreland and State of Pennsylvania, have invented and produced a certain new and original Design for Game-Boards, of which the following is a specification, reference being had therein to the accompanying drawings.

10 My invention relates to a new and original design for a game-board.

In the accompanying drawings, Figure 1 is a plan view of my new design, and Fig. 2 is a cross-sectional view taken on the line 2 2 of

15 Fig. 1.

As shown in the drawings, the leading or material feature of my design consists of the board 1, having the rectangular fields crossing each other at right angles and divided 20 into squares of equal size alternating in black

and white colors. Entirely surrounding the board is a ridge or flange 2, extending a slight distance above the upper surface of the board, and at each corner of the field is a cavity or recess 3, with fanciful scrollwork or ornaments 4 upon the board around each cavity or recess. Pins or legs 5, rigid with the under face of the board 1, extend downwardly therefrom as shown.

Having described my invention, what I claim as new, and desire to secure by Letters Patent, is—

The design for a game-board, as herein shown and described.

In testimony whereof I affix my signature 35 in the presence of two witnesses.

ALEXANDER J. BEISTEL.
